CONCRETE FLOORING

Kenneth J. Grove, 1020 E. 33rd Place, Tulsa, Okla.
Filed Mar. 20, 1961, Ser. No. 97,084
3 Claims. (Cl. 50—307)

The present invention relates to concrete flooring, and more particularly to concrete flooring of the type adapted to be spaced above ground level.

In the past, concrete flooring has been of two types: that which is laid on the ground, and that which is spaced above the ground. When the flooring is laid on the ground, it is inevitably subject to the absorption of ground moisture, so that wood flooring and carpeting rot and dampness is carried into the building. Also, when water pipes are installed under the flooring and it is necessary to reach these pipes for replacement or repair, it is necessary to break through the concrete and sometimes to ruin a whole slab when hunting for a leak. Concrete flooring that is spaced above ground level avoids these difficulties, but is difficult and expensive to construct, for it has heretofore been necessary to construct wooden forms, lay the concrete on the forms, let it harden, and then remove the forms.

Accordingly, it is an object of the present invention to provide concrete flooring spaced above ground level but which can be constructed without resort to wooden forms and the like.

Another object of the present invention is the provision of concrete flooring having means for automatically properly positioning reinforcing members in the flooring.

Finally, it is an object of the present invention to provide concrete flooring which will be relatively simple and inexpensive to manufacture and install, and which will be rugged and durable in use.

Other objects and advantages of the present invention will become apparent from a consideration of the following description, taken in connection with the accompanying drawing, in which:

FIGURE 1 is a fragmentary perspective view of a building with parts broken away showing the structure of novel concrete flooring according to the present invention.

FIGURE 2 is an enlarged fragmentary perspective view of a portion of FIGURE 1, showing particularly the relationship of the various portions of the reinforcing in the concrete.

FIGURES 3, 4 and 5 show successive steps in the assembly of flooring according to the present invention; and

FIGURE 6 is a fragmentary view of a supporting connection as formed by the steps of FIGURES 4 and 5.

Referring now to the drawing in greater detail, there is shown in FIGURE 1 a building indicated generally at 1 and having a foundation 3 that rests on the ground. The upper edge of foundation 3 is covered by a sheet of termite guard 5 that overhangs the upper edges of the foundation. The concrete flooring of the present invention, indicated generally at 7, is supported on top of termite guard 5.

Concrete flooring 7 includes as its principal supporting members a plurality of elongated horizontal parallel main support members 9 which are shown in the form of steel tubing but which, of course, could be solid rods or bars. Steel tubing, however, is preferred, for members 9 perform the dual function of reinforcing the concrete flooring and also of supporting the flooring on foundation 3. This latter function is achieved by the provision that opposite ends of support members 9 rest on foundation 3 on top of termite guard 5 and span the building between opposite sides of foundation 3.

Spaced a substantial distance below support members 9 is at least one horizontal uniplanar sheet of open-work

2

metal lath 11. Metal lath 11 is expanded sheet metal as shown in the illustrated embodiment; but it is to be understood that coarse wire screen or other open-work materials could also be used.

5 A very important feature of the present invention is the provision of parallel horizontal ribs 13 integral with metal lath 11 and having generally inverted V-shaped cross-sectional configuration as seen in FIGURE 6. The ends of ribs 13 rest on the upper ends of opposite side-walls of foundation 3, thereby to augment the support provided by main support members 9. Ribs 13 are integral with at least one adjacent uniplanar portion of metal lath 11, but extend up from the plane of the lath toward and are disposed against the undersides of support member 9. Ribs 13 run perpendicular to those main support members but are all parallel to each other.

Means are provided for integrating the metal lath and the main support members into unitary assembly, in the form of hangers 15 which may be bent from heavy wire. 20 Each hanger 15 has a mid-portion 17 which is initially bent to the hairpin shape shown in FIGURE 3, and a hooked end 19 at each end of the hanger. When mid-portion 17 is pinched into the loop shown in FIGURE 4, and then twisted to form the twist 21 shown in FIGURE 5, then it will be obvious that hooked ends 19 will be drawn up under the lower edges of inverted ribs 13 thereby to force those ribs firmly up against the underside of support members 9, but not to destroy the spacing between support members 9 and the plane of the open-work metal lath 11. It will also be understood that where sheets of metal lath meet edgewise, the inverted ribs 13 can simply be nested one within the other, for they are identical.

Once the metallic portion of the concrete flooring is assembled as described, it is necessary only to pour onto the supporting surface thus formed a quantity of concrete 23 consisting of the usual aqueous slurry of cement, sand and gravel. Care should be taken, however, that the gravel size is sufficiently large that the gravel will not readily pass through the holes of the open-work metal lath. If all the gravel were to pass through these holes, it is obvious that the cement would not remain on metal lath 11 but rather would fall to the ground below. Therefore, the concrete should not be runny, but rather should be what is known in this art as a "dry mix," that is, a relatively still as mixed. Concrete 23 should cover support member 9 and there should be a substantial depth of concrete above members 9. The concrete thus hardens on the support provided by metal lath 11, but even where support members 9 are closest to metal lath 11, there is concrete between the support members and the metal lath, thanks to ribs 13. Also, the distance between metal lath 11 and support members 9 is uniform over the entire 50 floor, thanks again to ribs 13. Finally, it is easy to use hangers resting on the support members 9 for integrating the support members and the metal lath, for the hooked ends of the hangers can easily fit under the lower edges of ribs 13 rather than tearing through the open-work metal lath itself, thanks again to ribs 13.

From a consideration of the foregoing, it will be obvious that all of the initially recited advantages of the present invention have been achieved.

Although the present invention has been described and illustrated in connection with a preferred embodiment, it is to be understood that modifications and variations may be resorted to without departing from the spirit of the invention, as those skilled in this art will readily understand. Such modifications and variations are considered to be within the purview and scope of the present invention as defined by the appended claims.

What is claimed is:

1. Concrete flooring comprising a plurality of elongated horizontal parallel main support members, horizontal open-work metal lath spaced below the support members, a plurality of parallel ribs integral with and extending upwardly from the plane of the metal lath and disposed transversely of and bearing against the underside of the main support members, the ribs comprising downwardly opening channels, hangers supporting the metal lath from the main support members and maintaining the ribs in contact with the main support members, each hanger being a single piece of wire straddling a main support member and having a hook at each end that extends downwardly through the openings of the metal lath and hooks under an edge of a said rib and terminates upwardly within the channel of the rib, each hanger having an upwardly extending loop above the associated main support member that is twisted to tighten the ribs against the main support members, and a quantity of concrete resting on the metal lath and surrounding the main support members on all sides and surrounding the twisted

loops, the gravel of the concrete being larger than the openings of the metal lath.

2. Concrete flooring as claimed in claim 1, both hooks of a given hanger engaging under the same edge of a given rib.

3. Concrete flooring as claimed in claim 1, the ribs being imperforate.
